WALL BRACKET FOR A TELEVISION SET

Richard H. Wann, 9205 Agnes St., Detroit, Mich.

Filed Nov. 20, 1961, Ser. No. 67,593

Term of patent 14 years

(Cl. D33—3)

FIG. 1

FIG. 3

FIG. 1 is a top plan view of a wall bracket for a television set embodying my new design, the television receiver being shown in broken lines for illustrative purposes only;

FIG. 2 is a front elevational view of the same.

FIG. 3 is a perspective view, with the two parts thereof shown separated for illustrative purposes only.

I claim:

The ornamental design for a wall bracket for a television set, as shown and described.
